UNITED STATES PATENT OFFICE.

CHARLES H. KERK, OF WAYNE, PENNSYLVANIA.

PROCESS OF MAKING PLATINUM-COVERED PINS.

1,081,451.

Specification of Letters Patent. Patented Dec. 16, 1913.

Application filed March 31, 1913. Serial No. 757,958.

To all whom it may concern:

Be it known that I, CHARLES H. KERK, a citizen of the United States, residing in Wayne, county of Delaware, State of Pennsylvania, have invented certain Improvements in the Process of Making Platinum-Covered Pins, of which the following is a specification.

The object of my invention is to improve the manufacture of platinum covered pins so as to insure the inclosing of the core with platinum.

The invention is particularly applicable for use in the manufacture of pins for dental purposes, such, for instance, as those which are employed to hold artificial teeth to their base. It will be understood that a pin of this type can be used for other purposes without departing from the essential features of the invention.

In the accompanying drawings:—Figure 1 is a side view of a dental pin made in accordance with my invention; Fig. 2 is a sectional view of the pin; Figs. 3 to 8, inclusive, are views illustrating different steps in the process of making the pin; Fig. 9 is a transverse sectional view on the line *a—a*, Fig. 5; Figs. 10 and 11, are views illustrating the process of making a different form of pin; and Fig. 12 is a view showing a modification of the method of reducing the ends of the pins.

Platinum covered pins have been used extensively for dental purposes and while the body portion of the core has been protected by the platinum casing, the ends have always been exposed. By my improved process the pins are finished and the core is entirely inclosed by the platinum covering.

The objection to the use of pins for dental purposes made entirely of an alloy of metal other than platinum, or a pin partly covered with platinum, has been that the alloy or core has been exposed to the acids of the mouth causing injury to the pins.

The pin of my invention has all of the advantages of a solid platinum pin at a greatly reduced cost.

In carrying out my invention, I first plate, or otherwise cover, a core which is preferably made of an alloy, such, for instance, as nickel or manganese, or combinations of other elements. After the core has been covered with the platinum, as in Fig. 3, I reduce the pin 1, as indicated in Fig. 4, to form a head 2 at each end. These heads

may be shaped in any manner according to the type of pin desired. In some instances, the pin may have but a single head, or, as in Figs. 10 and 11, it may be plain and of an even diameter throughout. The material between the heads of adjoining pins is then gradually reduced, preferably by the hammering, rolling, or swaging process, until a thin coupling is formed, as shown in Fig. 5. This coupling is then broken, leaving an exposed portion of the core surrounded by an annular flange 3, as in Fig. 6. I then remove, or reduce, the projecting portion of the core by mechanical means or by applying an acid, such as nitric acid, which will dissolve the projecting end of the core, leaving the blank, as shown in Fig. 7, with the flange 3 extending beyond the core a sufficient distance so that when the flange is turned down, it will completely inclose the core. The next step in the process is to turn down the flange, as in Fig. 8, by hammering, spinning, or burnishing, making a pin with a core entirely inclosed by a platinum covering. This construction is especially applicable for dental work.

Difficulty has been experienced in making the proper junction of the pin with the porcelain of the tooth, due to the fact that, in many instances, the core was exposed at the ends and, in some instances, gas bubbles would form in a tooth at the exposed end of the core and make an imperfect union between the pin and the tooth. It will be seen that I am enabled to completely inclose the core of a platinum covered pin, protecting the core and making a finished article which is particularly adapted for use in dental work.

I claim:

1. The process herein described, of making platinum coated pins; said process consisting in covering a core with platinum; indenting the pin at intervals to reduce its diameter; severing the pin at the reduced portions; and then turning over the platinum covering onto the exposed portion of the core.

2. The process herein described, of making platinum coated pins; said process consisting in covering a core with platinum; making annular indentations at intervals in the core and its platinum covering; severing the pin at the reduced portions, leaving an annular flange of platinum surrounding the exposed portion of the core, then apply-

ing an acid to the exposed portion of the core to remove the projecting portion thereof; and turning down the flange onto the core, thereby inclosing the end of the core and making a completely covered article.

3. The process herein described, of manufacturing platinum coated dental pins; said process consisting in covering a core with platinum; pressing the core at intervals to form annular projections and making a deep recess between the two adjoining projections; severing the core and the platinum covering at the depressions, leaving the re-

duced portion of the core exposed surrounded by a flange of platinum; reducing 15 the projecting portion of the core; and turning down the flange onto the core so as to entirely inclose the core within the platinum covering.

In testimony whereof, I have signed my 20 name to this specification, in the presence of two subscribing witnesses.

CHARLES H. KERK.
